UNITED STATES PATENT OFFICE

GEORGE W. RANDALL, OF WASHINGTON, DISTRICT OF COLUMBIA

BEDPAN

Application filed May 28, 1931. Serial No. 540,748.

This invention relates to a bed pan, one of the objects being to provide a device of this character by means of which certain classes of patients can bring themselves to sitting postures thereon and thereby relieve the attendant nurses from much of the heavy lifting otherwise required of them.

A further object is to provide a structure utilizing an outer housing or body portion and a removable container therein, it being possible to use both jointly or to use the container independently of the other portions of the device.

Another object is to provide both the housing and the container with closures for sealing them after use and preventing the escape of odors into the room when it is impossible to promptly remove the complete device or the container from the room.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings:

Figure 1 is a vertical longitudinal section.
Figure 2 is a plan view.

Figure 3 is a section on line 3—3, Figure 2.
Figure 4 is a section on line 4—4, Figure 3.

Referring to the figures by characters of reference, 1 designates a box-like main portion of a housing open at one end while its other end is formed with an extension 2 the edge of which can be rounded as at 3 while the top is inclined upwardly from said edge to the top of the main portion 1. An opening 4 is formed in the top of the main portion and can be closed by lids 5 hingedly connected to the sides of the housing and adapted to rest snugly on the top when in closed position so as to practically seal the opening.

The housing has standards 6 at the sides thereof to which are secured side rails 7 con-

nected at their front ends by a cross rail 8. Grips 9 are located at the back ends of the side rails.

A removable container 10 is insertable into the housing through the open end thereof and has a tapered extension 11 adapted to be seated in the extension 2. The outer end of the container acts to close the open end of the housing, there being flanges 12 provided for that purpose. The container is operated like a drawer and can be pulled out and pushed in by means of a handle 13.

Side flanges 14 are formed on the container at the top thereof and constitute side grips whereby the container can be carried readily. Slides 15 are movably mounted under these grips in slots 16 formed in the sides of the container and these slides work in guides 17 provided therefor in the container. Flanges 18 are carried by the slides and serve to close the slots when the slides are pushed toward each other. Knobs 19 can be connected to the slides to facilitate their operation.

An opening 20 is formed in the top of the container 10 where it will lie directly under opening 4 and when the two slides 15 are pushed toward each other they will come together at their inner ends beneath the opening and close the top of the container.

The entire device can be made of light material and can be placed on a bed with the extension 2 projecting under the patient. The patient by pulling on the grips 9 can then be brought readily to a sitting posture on the main portion 1, it being understood that the lids 5 are first swung upwardly and laterally against standards 6. The slides 15 are also first moved to open positions.

After there is no further use for the device and the patient has been restored to a reclining position, the lids 5 can be closed and the entire device set aside. The container can be withdrawn and the slides closed and thereafter other containers can be used in the housing.

Under some conditions the container can be used independently of the housing as will be obvious. It can be handled readily by means of the side flanges 14 and it is possible

readily to shift the slides either to open or to seal the container.

What is claimed is:

5. 1. A bed pan including a portable housing having an extension, there being an opening in the top of the housing, hinged covers for the opening in the top of the housing, a container removably mounted in the housing and having a top opening, and side slots, 10 slides in the slots for closing the top opening therein, and side flanges on the container overhanging the outer ends of the slides when closed.
15. 2. A device of the class described including a portable housing having an extension, side rails connected to the housing, there being an opening in the top of the housing, hinged covers for the opening in the top of the housing, a container removably mounted in the 20 housing and having a top opening, and side slots, slides in the slots for closing the top opening, guides therefor, means on the slides for closing the slots when the opening is closed, and flanges on the container overlying the outer ends of the slides when closed and forming grips.
30. 3. In a device of the class described a container having an opening in the top thereof and an inclined extension at one end, slots in the sides of the container, guides, slides in the slots and guides for closing said slots and the opening, and side grips on the container overlying the outer ends of the slides when closed.
35. 4. In a bed pan a container having an opening in the top thereof and an inclined extension at one end, slots in the sides of the container, slides in the slots for closing said slots and the opening, and side grips on the container overlying the outer ends of the slides when closed.

In testimony that I claim the foregoing as my own, I have hereto affixed my signature.

GEORGE W. RANDALL.
